Patented Jan. 13, 1920.

FIG-1-

FIG-2.

Inventor.
William W. Hill
by Robert W. Denner
Attorney.

UNITED STATES PATENT OFFICE.

WILLIAM WASHINGTON HILL, OF SARONA, WISCONSIN.

REGULATOR FOR ENGINES.

1,327,999.

Specification of Letters Patent. Patented Jan. 13, 1920.

Application filed April 10, 1919. Serial No. 289,109.

To all whom it may concern:

Be it known that I, WILLIAM W. HILL, a citizen of the United States, residing at Sarona, in the county of Washburn and State of Wisconsin, have invented certain new and useful Improvements in Regulators for Engines, of which the following is a specification.

This invention relates to devices for regulating engines used for pumping water and other liquids into tanks; and it consists in the novel construction and combination of the parts hereinafter fully described and claimed whereby the engine is stopped when the liquid in the tank rises to a predetermined height.

In the drawings, Figure 1 is a front view of a regulating mechanism constructed according to this invention. Fig. 2 is a plan view of the same.

A tank 2 for the liquid is provided, and 3 is its inlet pipe which is connected to the pump. The pump is of any approved kind, preferably driven by an internal combustion engine, and the pump and its engine are not shown as they are of any approved construction. A suitable stationary support 4 is arranged adjacent to the tank, or in any other convenient position, and 5 is a catch which is pivoted at its middle part on a pin 6 which projects laterally from the support. One end portion of the catch has a notch 7 in its underside, and 8 is an arm which projects upwardly from the other end portion of the catch.

A flexible connection 9, such as a cord, or chain, is secured to the upper end of the arm 8. This flexible connection 9 passes over a guide sheave 10 which is carried by an arm 12 which projects from the support 4, and it has a float 14 on its free end which depends within the tank. A catch spring 15 is attached to the same end portion of the catch as the arm 8 and is secured to the support 4. The float is made of such weight that it will hold the catch in the position shown in Fig. 1 with the catch spring extended and under tension, as long as the float is above the top of the liquid in the tank.

An actuating lever 18 is pivoted to the support 4 by a pin 19, and its free end 20 is pointed and arranged to engage with the

notch 7 of the catch when in the position shown in Fig. 1. A strong actuating spring 21 is provided, and is secured at one end to the support 4, with its free end portion bearing against one side of the actuating lever 18. A bumper or stop 24 projects from the support 4 for the actuating lever 60 to strike against when released from the catch.

An actuating device 26, such as a cord, chain or rod, is connected to the upper end portion of the actuating lever, and is preferably provided with three branches 27, 28 and 29. When the pump is driven by an internal combustion engine, these three branches are connected to the gas valve, the electric switch, and the lubricator of the engine, so that all of these parts may be actuated simultaneously.

A cord 30 is also attached to the lever, and may be connected to a hook 31 on the support 4, so as to hold the actuating lever in an inoperative position when the engine is not being used to drive the pump.

When the liquid in the tank rises so that it raises the float, it permits the catch spring to raise the catch out of engagement with the point of the actuating lever, which is then forced over against its stop by the actuating spring, thereby pulling on the actuating device and stopping the engine.

What I claim is:

In an engine regulating device, a pivoted actuating lever operatively connected with the engine, an actuating spring for moving the said lever pivotally in one direction, a pivoted catch having a notch at one end which normally engages with the said lever and prevents it from being moved by the actuating spring, said catch having a projecting arm at its other end portion, a tank for liquid, a float adapted to be raised by the liquid in the tank, a guide sheave, a flexible connection passing over the guide sheave and connected to the said arm at one end and to the float at the other end, and a catch spring which operates the catch and releases the actuating lever when the float is raised by the liquid in the tank.

In testimony whereof I have affixed my signature.

WILLIAM WASHINGTON HILL.
